[57] **CLAIM**

The ornamental design for a drawing implement holder for mounting on a drawing table, as shown and described.

DESCRIPTION

FIG. 1 is a perspective view of drawing implement holder for mounting on a drawing board showing my new design;

FIG. 2 is a right side elevational view thereof, the opposite side being a mirror image thereof, the dotted line structure being for illustrative purposes only and not a part of the design;

FIG. 3 is a bottom plan view thereof;

FIG. 4 is a bottom plan view thereof, an intermediate portion being broken away for convenience of illustration;

FIG. 5 is a front elevational view thereof; and

FIG. 6 is a rear elevational view thereof.

FIG. 1

FIG. 2

FIG. 3

FIG. 4

FIG. 5

FIG. 6
